UNITED STATES PATENT OFFICE.

DAVID HILL, OF LEICESTER, ENGLAND.

DESIGN FOR A HEEL FOR BOOTS AND SHOES.

Application filed August 3, 1921. Serial No. 489,649. Term of patent 7 years.

To all whom it may concern:

Be it known that I, DAVID HILL, subject of the King of Great Britain, residing at Leicester, in the county of Leicester, England, have invented a new, original, and ornamental Design for a Heel for Boots and Shoes, of which the following is a specification, reference being had therein to the accompanying drawing.

Figure 1 is a perspective view of a heel showing the design.

Figure 2 is a side view, and Figure 3 is a back view of the same.

What I claim as new, and desire to secure by Letters Patent, is:—

The ornamental design for a heel for boots and shoes as shown.

In testimony whereof I affix my signature in presence of two witnesses.

DAVID HILL.
